CLAIM

The ornamental design for a cube-like puzzle, as shown and described.

DESCRIPTION

FIG. 1 is a perspective view of the puzzle of our design depicting three sides of the cube-like puzzle in its unmanipulated state; and,

FIG. 2 is a perspective view showing the three sides of our design not depicted in FIG. 1 with the puzzle of our design in its unmanipulated state.

Our design is characterized by it being comprised of a plurality of linked segments capable of being manipulated to a multitude of configurations.

FIG. 1

FIG. 2
